UNITED STATES PATENT OFFICE.

GEORGE E. PATTERSON, OF GREENWICH, CONNECTICUT.

DOWEL PINHOLE-BORING MACHINE.

Application filed September 14, 1923. Serial No. 662,632.

To all whom it may concern:

Be it known that GEORGE E. PATTERSON, a citizen of the United States, residing at Greenwich, in the county of Fairfield and State of Connecticut, has invented certain new and useful Improvements in Dowel Pinhole-Boring Machines, of which the following is a specification.

This invention is in the way of a dowel pin 10 boring machine, for the use of carpenters and mechanics generally, and the object of the invention is to provide a simple, practical and efficient tool to facilitate the centering and aligning of the boring bit of a hand brace in the process of boring dowel 15 pin holes in wood stock of any kind. The tool is of especial value where many such holes are to be bored in a regular and uniform run of stock.

20 In the drawings—

Figure 1 is a top plan view of the device; Figure 2 is a front elevation; Figure 3 is a side elevation; Figure 4 is a rear elevation;

25 Figure 5 is a bottom view;

Figure 6 is a longitudinal vertical section;

Figure 7 is a detail of the bit cradle and attachments;

30 Figure 8 is a detail of the tool bed elevator dogs as mounted in connection with the shoes;

Figure 9 is a detail of the sliding lock mechanism and centering scale thereon.

Fig. 10 is a detail of an angle plate.

35 In carrying out this invention, I provide two shoes 1, which may be made of cast metal and angular in cross section as shown. These shoes are designed to be secured horizontally and in spaced parallel relation, per-

40 pendicularly to the front edge of the ordinary work bench 3; and for this purpose, anchor lugs 4 are formed integrally upon the lower edges of the shoes, the said lugs being pierced with screw holes, through which the screws 5 are inserted into the bench 3. The 45 shoes 1 are formed with upper ribs 6 at the back ends thereof, and lower ribs 7 at the front ends thereof, the two lying in different, spaced and parallel, horizontal planes and

50 being connected by short ribs 8 which join the ribs 6 and 7 at an angle of approximately 35 degrees from the horizontal. The shoes 1 carry integrally formed feed screw lugs 9 at their front ends which are turned laterally inward and faced off underneath

at an angle of about 55 degrees from the horizontal, so that the faces 10 lie in a plane perpendicular to the extended plane of the connecting ribs 8. Elongated elevator dogs 11 are also formed integrally with the shoes 1, the dogs being located on the inner sides of the shoes and set at an angle of 35 degrees thereon so as to correspond to the inclination of the ribs 8. A stock bed 12 is secured across the upper ribs 6 of the shoes 1 by screws 13 passed up through the ribs 6 into the bed 12. A tool bed 14 is mounted and adapted for vertical adjustment upon the lower ribs 7, by means of angle-plates 15 secured to the under side of the bed 14 by screws 16, adjacent the inner sides of the shoes 1. These angle-plates 15 have integrally formed elevator dogs 17 set at an angle of 35 degrees and adapted to 60 slidingly intermesh with the similar dogs 11 65 on the shoes 1. Feed screw anchor plates 18 are secured by screws 19 to the front edge of the bed 14, and these plates have downwardly and inwardly turned lips 20 pierced with holes 21, the lips 20 standing immediately back of and substantially parallel to the faces 10 of the lugs 9. The lugs 9 are pierced with threaded holes 22, and feed screws 23 are passed through these holes, 70 their inner reduced ends 24 passing through the holes 21 of the anchor plates 18 and being there rotatively secured by means of cotter pins 25 passed through the said ends back of the lips 20. It is now apparent that 75 by turning up the feed screws 23, the tool bed 14 will be pushed upwardly, the dogs 17 80 moving over the dogs 11 of the shoes 1.

A U-shaped clamp opening 26 is cut through at the central back edge of the bed 14. A scale strip or fence 27 is secured 85 vertically along the back edge of the bed 14, the same having an integrally formed central fence block or bit guide block 28, through which the bit guide hole 29 is cut 90 perpendicularly to the face of the fence 27. This hole is made sufficient large, so that the bushing 30 may be mounted therein and releasably locked in place by a set screw 31 passed down through the top of the block 28. By using bushings of various degrees of thickness, a suitable guide 95 may be formed for bits of various sizes. A centering point 32 projects rearwardly from the block 28. Slots 33 are cut through the fence 27 at each side of the block 28, the 100

105

110

said slots being elongated horizontally; and sliding guides 34 are mounted back of the fence 27 at the slots 33, and freely held in place by means of threaded pins 35 fixed 5 in the guides and extended through the slots, and with thumb nuts 36 mounted on the ends of the pins. Calibrated scales 37 are marked on the fence 27 at each side of the centering point 32, and thus means are afforded for adjusting the guides 34 for the 10 boring of small stock. For large or wide stock, the guides 34 may be removed from the fence. For holding the stock firmly to the stock bed 12, clamping means are provided, consisting of curved clamp arms 38 having their lower ends secured by screws 39 to the under side of the stock bed 12 at the forward edge thereof, and having their upper ends connected by the integrally 15 formed clamp plate 40 through which the threaded hole 41 is cut. A clamp screw 42 is then mounted through this hole 41 and its lower end is rotatively anchored to a clamp 43. In order to steady the 20 clamp 43, guide pins 44 are extended vertically therefrom and slidingly passed through holes 45 in the ends of the plate 40. A bit cradle 46 is mounted at the front edge of the tool bed 14 and centrally aligned 25 with the guide block 28. This cradle includes a bed plate 47, concaved centrally at 48 to accommodate the chuck of a brace, and having four integral spindle posts 49, one at each corner thereof. The plate 47 is 30 secured to the front edge of the tool bed 14 by screws 50. The posts 49 are pierced with spindle holes 51 and spindles 52 are slidingly mounted therethrough, one spindle at each side of the cradle. A guide bar 35 35 40 45 50 55 60 65 70 75 80 85 90 95 100 105 110 115 120 125 130

53 spans the spindles 52 and is releasably locked thereto. For this purpose, the bar is pierced at each end with a hole 54, through which the spindle is passed, and set screws 55 are then passed through the ends of the bar 53 and seated against the spindles. The bar 53 is provided with a central bit slot 56 cut down thereinto through the upper edges, and a locking gate 57 is pivoted at 58 to the bar 53 and has a central bit slot 59 cut therein, upwardly through the lower edge, the said slot being complementary to the slot 56, and the two serving together to completely embrace the shank of the bit 60 mounted in the apparatus. The gate 57 has a latch slot 61 cut at its free end and adapted to engage a screw 62 set in the bar 53, for locking the gate 57 in closed position. Two stops 63 and 64 are provided and may be demountably set upon the shank of the bit 60, one at each side of the bar 53. For this purpose, slots 65 are cut through the outer edges to the center and set screws 66 are passed laterally through and adapted to bear upon the shank of the bit. The outer stop acts

as a depth stop to prevent the bit entering too far into the stock, and the inner stop serves both to draw back the bar 53 when the bit is withdrawn from the stock, and also to prevent the bit from leaving the bushing 30. Sliding gauge locks 67 are mounted one at each side of the device and provide means for locking the bed 14 at any desired point in its travel on the intermeshing dogs 17 and 11. These locks include links 68 pivoted at 69 to the ends of the stock bed 12 and have slots 70 cut therein. Threaded pins 71 are extended from the end of the tool bed 14 out through the slots 70, and nuts 72 are mounted on the ends of these pins. Gauge notches 73 are cut along the upper edges of the links 68. By manipulation of the feed screws 23, the bed 14 and the bit 60 may be elevated as required in order to vertically center the bit to the stock being worked upon, after which the bed 14 may be locked in that position by turning up the nuts 72. In the drawing the three gauge notches 73 indicate the points at which the bed 14 must be locked in order to center the bit for $\frac{7}{8}$ " stock, $1\frac{1}{8}$ " stock and $1\frac{3}{8}$ " stock, respectively.

While I have herein described a certain specific manner and method of constructing and assembling the elements of my invention, it is understood that I may vary from the same in minor details, not departing from the spirit of my invention, so as best to construct a practical device for the purpose intended, as defined in the appended claims.

I claim:

1. A device of the kind described, comprising shoes positioned horizontally in parallel spaced relation, the same having lower rearwardly extended stock bed ribs, and forwardly extended and relatively lower tool bed ribs, the latter ribs having integrally formed elongated dogs on their inner sides and inclined upwardly from their front ends to their back ends; a stationary stock bed on the rear ribs of the shoes; a vertically adjustable tool bed having elongated inclined dogs at its side edges complementary and slidingly intermeshing with the dogs of the said shoes; means for clamping the stock to the stock bed; and means for adjustably supporting the bit on the tool bed and centering the bit to the stock.

2. A device of the kind described, comprising shoes positioned horizontally in parallel, spaced relation; elongated, spaced dogs on the inner sides of the forward ends of the shoes, the same being inclined upwardly from front to back; a stationary stock bed mounted transversely on the rear ends of the shoes; a vertically adjustable tool bed mounted transversely on the forward ends of the shoes; elongated, spaced dogs at the side edges of the tool bed com-

plemental to and slidingly intermeshing with the dogs of the shoes; means for clamping the stock to the stock bed; means for adjustably supporting the bit on the tool bed; and separate means for centering the bit laterally upon the stock.

3. A device of the kind described, comprising shoes positioned horizontally in parallel, spaced relation; elongated, spaced dogs on the inner sides of the forward ends of the shoes, the same being inclined upwardly from front to back; a stationary stock bed mounted transversely on the rear ends of the shoes; a vertically adjustable tool bed mounted transversely on the for-

ward ends of the shoes; elongated, spaced dogs at the side edges of the tool bed complementary to and slidingly intermeshing with the dogs of the shoes; means for clamping the stock to the stock bed; means for 20 adjustably supporting the bit on the tool bed; separate means for centering the bit laterally upon the stock; and means dependent upon the interplay of the said intermeshing dogs of the tool bed and shoes 25 for vertically adjusting and supporting the tool bed relative to the stock bed.

In testimony whereof I affix my signature.

GEORGE E. PATTERSON.
